UNITED STATES PATENT OFFICE.

SAMUEL A. POTTER, OF WASHINGTON, DISTRICT OF COLUMBIA.

KITE.

SPECIFICATION forming part of Letters Patent No. 607,129, dated July 12, 1898.

Application filed September 24, 1897. Serial No. 652,892. (No model.)

To all whom it may concern:

Be it known that I, SAMUEL A. POTTER, of Washington, in the District of Columbia, have invented a new and useful Improvement 5 in Kites, of which the following is a specification.

This invention has reference to kites, and relates more particularly to what are known as "cellular" kites—that is to say, kites composed of two or more open cells—presenting a series of surfaces as distinguished from those composed of a single surface.

The object of the invention is to provide a kite which will combine simplicity of construction, strength, and lightness and the cells of which will be of such form as to present an increased sustaining-surface and insure steadiness in flying.

With these ends in view my invention consists, primarily, of forming the cells with inwardly and downwardly inclined side surfaces as distinguished from vertical side surfaces.

The invention also consists in maintaining 25 the form of the cells by two main trusses extending across one another between the opposite corners of the cells.

The invention also consists in connecting 30 the cells by longitudinal rods extending from the corners of one cell to the opposing corners of the other.

The invention also consists in the details of construction and combination of parts hereinafter described and claimed.

35 In the accompanying drawings, Figure 1 is a perspective view of a kite having my invention embodied therein and in its preferred form. Fig. 2 is a vertical transverse sectional elevation through one of the cells on the line 40 *aa* of Fig. 3. Fig. 3 is a side elevation of the kite. Fig. 3^a is a side elevation in a slightly-modified form. Fig. 4 is a perspective view of one of the sockets by which the vertical struts are detachably connected to the upper 45 and lower bars of the cells. Fig. 5 is a perspective view of the end of the horizontal strut, showing the manner in which it is detachably connected to the side bars of the cells. Fig. 6 is a perspective of my kite, showing 50 the cells of a different form. Fig. 7 is a front elevation of the same.

Referring to Figs. 1, 2, and 3, my improved kite in its preferred form is composed of a front cell 1 and a rear cell 2, identical in form and construction and diamond-shaped 55 in cross-section, thereby presenting each two downwardly and inwardly inclined side-sustaining surfaces 3 and 4. Each cell consists of a frame comprising an upper longitudinal bar 5, a lower bar 6, parallel to it, and two longitudinal side bars 7. These bars are maintained in position the proper distance apart by vertical and horizontal struts 8 and 9, which cross each other and which are connected at their ends to the upper and lower and side bars, 60 respectively. The two frames thus formed are connected together in a single frame by forming all the longitudinal bars continuous; but it is obvious that the upper and lower bars only may be continuous, the other two being 65 separated between the cells, as shown in Fig. 3^a. The sustaining-surfaces of the cells are formed by extending around the four longitudinal bars at their front and rear ends, where they are trussed, two bands of some suitable 70 material—such as silk, linen, or other light fabric—which is fastened to the bars where it passes over the same and drawn tightly, thereby forming two diamond-shaped cells presenting downwardly and inwardly inclined side- 75 sustaining surfaces, as clearly shown in Figs. 1 and 2. The width of the material composing the cell-surfaces is such that the cells will be separated by a suitable space, thus permitting such action of the air-currents as 80 85 will insure the proper suspension of the kite in the air.

By forming the cells diamond-shaped, as described, each side of the cell presents a distinct sustaining-surface, and by reason of 90 the downward and inward inclination of the lower sustaining-surfaces the air-currents will tend by acting equably on its inclined surfaces to steady the kite and prevent it from darting.

95 It will be observed that to maintain the shape of the cells I employ two struts for each cell, which cross each other and which extend from the opposing corners of the cells. This arrangement produces a frame simple in 100 construction and of minimum weight, and in connection with the extended sustaining-sur-

faces of the cells the kite possesses the features which are most favorable for effective action in flying.

When flying, the kite assumes a position 5 inclined upward at an angle of about twenty degrees, as shown in Fig. 1, in which position the front cell-surfaces deflect the air-currents to the rear cell, and it is due to this interference of the currents that the kite is properly 10 suspended in the air.

In the drawings I have shown the struts 8 and 9 detachably connected to the longitudinal cell-bars to produce a collapsible frame for convenience in packing and transporting.

15 This result may be accomplished by various means, but I prefer the construction shown as being simple and effective. On reference to Figs. 2, 4, and 5 it will be seen that each of the upper and lower bars has fixed to it 20 inwardly-extending metal sockets 10, which receive the ends of the vertical struts. These sockets are formed with lips 11, which embrace the bars, and with side flanges 12, bearing on the bars to maintain the position of 25 the sockets. The ends of the struts are formed to fit snugly in the sockets and may be removed therefrom when it is desired to collapse the frame. Each of the horizontal struts has its ends forked, as shown in Fig. 5, to 30 straddle the side bars, the forked ends being conveniently formed by notching the ends of the strut, as at 13, and applying thereto a cleat 14. To prevent the strut from slipping along the bars, the latter are recessed, as at 35 15, to receive the notched end of the strut.

The belly-band or bridle of a kite of this form consists of a loop 16, attached at its ends to the lower longitudinal bar 6 at about the centers of the cell-surfaces, the loop being 40 secured to the main flying-string 17.

In Fig. 6 I have shown a modified form of my kite. In this case instead of forming the cells diamond-shaped they are of trapezoidal form, with upper and lower parallel surfaces 45 18 and 19 and with two downwardly and inwardly inclined surfaces 20. The shape of these cells is maintained in a manner similar to the diamond-shaped cells—that is, by two truss-rods 21, which extend diagonally 50 across one another from the diagonally opposite corners of the cells. The two cells are connected by the longitudinal rods 22, and the bridle or belly-band consists of a loop 23, attached at its ends to the lower corners of 55 the front cell, and to this loop the main flying-string 24 is secured.

In both of the forms of kites described it is seen that the cells present each four sustaining-surfaces, two of which are inclined downward and inward to insure steadiness in flying, and that, further, in both cases the shape

of these cells is maintained by but two struts, which arrangement combines extreme lightness with simplicity and increased sustaining-surface.

65

Having thus described my invention, what I claim is—

1. The improved kite comprising a plurality of open-ended cells having downwardly and inwardly inclined sustaining-surfaces, 70 and suitable connections between said cells maintaining them in fixed relations.

2. The improved kite comprising a plurality of open-ended, four-sided cells, said cells having two of their sides inclining inward 75 and downward toward each other, and suitable connections between said cells maintaining them in fixed relations.

3. In a cellular kite the combination with a cell, of longitudinal bars at the corners thereof and two truss-rods crossing each other and connected at their ends to the bars at the opposing corners of the cells.

4. The improved cellular kite composed of a plurality of diamond-shaped, open-ended 85 cells, and suitable connections between said cells maintaining them in fixed relations.

5. The improved cellular kite comprising a plurality of diamond-shaped, open-ended cells, vertical and horizontal struts crossing 90 each other and extending between the opposing corners of said cells, and suitable connections between said cells maintaining them in fixed relations.

6. The improved cellular kite consisting of 95 an upper longitudinal bar 5, a lower longitudinal bar 6 extending thereunder and parallel to the same, two longitudinal side bars 7 extending on opposite sides of the upper and lower bars and about midway between the 100 same, vertical struts 8 connected at their ends to the upper and lower bars, horizontal struts 9 crossing the vertical struts and connected at their ends to the side bars, and bands or coverings applied to said longitudinal bars, 105 inclosing the struts and extending diagonally from bar to bar and forming inclined sustaining-surfaces at the front and rear of the kite.

7. The combination with a cellular kite having front and rear diamond-shaped open-ended cells, and upper and lower longitudinal bars connecting said cells, of a bridle or belly-band connected to the lower longitudinal bar and adapted to be attached to the main string.

In testimony whereof I hereunto set my 115 hand, this 20th day of September, 1897, in the presence of two attesting witnesses.

SAMUEL A. POTTER.

Witnesses:

CHARLES E. RIORDON,
W. R. KENNEDY.
